PUMP AND UNLOADING MEANS

Charles L. Rayfield, Chicago, Ill., assignor, by
mesne assignments, to Thermal Units Manu-
facturing Company, a corporation of Illinois

Application January 2, 1935, Serial No. 28

2 Claims. (Cl. 103—41)

The present invention relates to an improved fluid pump and unloading means for automatically equalizing the pump discharge and inlet pressures as soon as the pump is stopped, where-
5 by starting of the pump is greatly facilitated.

In the Solomon E. Koplar Patent No. 1,986,584, issued January 1, 1935, covering "Refrigerant pumping systems", there is described a refrigerant pumping system utilizing a pump of the 10 same general construction and operation as the pump described herein, and to which the present invention has been applied, although it will be apparent to one skilled in the art that the invention in its broad concept may be utilized with 15 other types of pumps.

In the above mentioned patent oil under pressure is applied in the common chamber between the angularly disposed pumping sections for lubricating and sealing the pump parts.

20 A feature of the present invention resides in the provision of a thrust spring for each of the rotative pump cylinders, these springs being so mounted as to resiliently force the associated cylinders against their seats, whereby it is un-
25 necessary to rely entirely upon oil pressure in the common chamber to assure proper seating of the cylinders.

A further object of the invention resides in the provision of improved means for automatically 30 equalizing the pump inlet and outlet pressures, when the pump is stopped.

To this end there is mounted at one end of 35 one of the pumping sections, a pair of disc members which are arranged for separating move-
ment, one of these members being connected for rotation with the pump cylinder, and provided with an annular inclined upper surface. A plu-
40 rality of balls are disposed between the afore-
mentioned disc members, these balls being re-
tained for rotation with the discs, but free to move outwardly under the influence of centrifugal force over the inclined surface into engagement with the other of the discs. It will there-
fore be seen that as these balls are thrown out-
45 wardly, when the pump reaches a pre-determined speed, they act as wedges to force the discs apart. Advantage is taken of this relative movement of the discs to operate a valve disposed in a by-pass connection between the fluid inlet and outlet of 50 the pump.

Other objects and advantages of the present invention will more fully appear from the following detailed description taken in connection with the accompanying drawing which illustrates a 55 single embodiment thereof, and in which:

Figure 1 is a view in elevation of a pump embodying the features of the present invention and having broken away portions to show certain details of the pump parts in section;

Figure 2 is an enlarged transverse sectional view taken through the centrifugally actuated valve control means, taken substantially on line II—II of Figure 1; and

Figure 3 is a detailed plan view of one of the disc members of the centrifugally operable valve 10 control means, showing the annular groove defining an inclined surface on its face.

As shown on the drawing:

As illustrative of my invention, I have chosen to show in Figure 1, pumping apparatus embodying the features of the present invention, which apparatus is adapted for use in a system requiring fluid to be circulated therethrough under pressure, such as in a refrigerating system. Since my invention is primarily concerned with improvements in the pump and means for equalizing the pressure between the inlet and outlet connections for the fluid to be pumped, when the pump is stopped, it is deemed unnecessary to show the details of the pumping system, as these would be of conventional design. Consequently, the inlet and outlet connections with check valves therein, which would ordinarily be connected into the circulatory system, have been shown in their relation to the pump proper.

20 In general, the pump comprises a pair of angularly disposed pumping sections A and B which are in end to end relationship and define at their juncture, a common chamber 10.

The pumping elements in each of the pumping sections are similarly constructed and operate in the same manner. As a matter of fact, the sections A and B operate in multiple and have their inlet and outlet connections inter-connected. For this reason, in describing the present invention, reference will be made to the pumping instrumentalities of one section only.

30 Each section defines a tubular casing within which there is rotatably mounted a cylinder 11 having a plurality of longitudinally extending 35 bores 12 which are angularly spaced at equal intervals around the center of rotation of the cylinder. These bores are adapted to receive therein a plurality of sets of pistons 13, one piston of each set being disposed in one of the bores 40 in the pumping section B and the other piston of that particular set being disposed in one of the bores of the cylinder in section A. It will now be evident that when the cylinder in the pumping section B is rotated by a drive shaft 14, which 45

may be connected to a suitable source of power, the sets of pistons will act as a coupling between the cylinder in section B and the cylinder in section A, thereby causing the cylinders to rotate and the pistons to be reciprocated within their associated bores.

Each of the rotatable cylinders is seated on a seating disc 15 and the seating surface of the cylinder is provided with port openings from each 10 of the bores 12, these port openings being adapted to engage with a suitably disposed intake and discharge port which are connected to an intake line 16 and discharge line connection 17.

The pump as thus described is well known in 15 the art, and it is therefore deemed unnecessary to describe it in further detail.

Heretofore, it has been the usual practice to conduct oil into chamber 10 under pressure for the purpose of forcing the cylinders in the pumping 20 sections against their seats and lubricating and sealing the pumping parts.

In the present construction, it is proposed to provide a thrust spring which will resiliently force the rotatably mounted cylinders against 25 their seats. Referring to Figure 1, the cylinder 11 is provided with a central stem or shaft 17 at its seat end, this shaft being extended through a suitable opening 18 in the end of the housing, and supported in an anti-friction bearing 19. 30 In the present instance, the anti-friction bearing is shown as comprising the usual type of ball bearings wherein the balls are contained between an inner and outer ball race.

The outer end of the shaft 17 is provided with 35 a contracted threaded portion 20 which defines a shoulder 21 against which a disc or washer 22 is held in abutting relationship by means of a nut 23. This disc projects outwardly past the outer surface of the shaft 17 and provides an abutment 40 for one end of a compression spring 24 having its other end abutting against the inner ball race of the anti-friction bearing 19. This spring, it is evident, will function to longitudinally force the shaft 17 towards the associated end of the 45 pumping section with the result that the cylinder 11 is forcibly seated against the seat block or disc 15.

The outer end of the pumping section A is counter-bored as shown at 25 and has disposed 50 therein the anti-friction means 19 which was mentioned above. There is also mounted in the counterbore 25, a collar or sleeve 26 which terminates at its outer end in an annular ring shaped portion 27 which serves as a retainer for anti- 55 friction means 28. The anti-friction means 28 rotatably supports a contracted hub portion 29 of a disc 30 which is secured to the shaft 17 for rotation therewith.

Spaced above the disc 30 is a second disc 31 60 which is provided on its lower surface with a depending stem 32 which is disposed in a central socket 33 of the disc 30.

The stem and socket connection between the discs 30 and 31 enables the discs to be axially 65 shifted away from and towards each other.

Surrounding the stem 32 and disposed between the discs 30 and 31 is another disc 34 which is provided with axially extending slots 35 for receiving therein in each case a ball 36. It will be 70 evident that the ball is free to move radially and also axially relative to the disc 34. Moreover, rotational movement of the disc 34 will cause the ball to bodily revolve around the stem 32.

Referring to Figure 3, the upper surface of the 75 disc 36 is circumferentially grooved to define an

outwardly and upwardly slanting surface 37, so that as the balls 36 are moved outwardly by centrifugal action, the balls will be raised slightly and contact the confronting surface 38 of the disc 31 to shift the disc 31 away from disc 30.

For encasing the mechanism just described, there is provided a cap 39 which terminates at 5 its base portion in an outstanding flange 40 which is secured as by bolts 41 to the end of the pumping section A.

This cap defines a chamber 42 which is in communication by means of passageways 43 and 44 with the inlet and outlet connections 16 and 17 respectively.

In axial alignment with the center line of rotation of the disc 31, there is disposed a bushing 45 having a central bore which provides an extension for the passageway 44 and also serves as a valve seat for a cooperating valve pin 46. This bushing is provided with a diametral slot 46a 20 which serves as a guide for a pin 47a supported in the valve pin 46.

The valve pin 46 is slidably supported in a socket 47 which is disposed in the hub portion of the disc 31, this socket opening on the upper side 25 of the disc. At the inner end of the socket, the valve pin is supported on a thrust ball member 48. The pin 47a maintains the pin 46 against movement relative to its seat.

The inlet and outlet connections 16 and 17 are 30 provided with suitable check valves 49 and 50 respectively.

The operation of the valve and its control means will now be considered. When the pump is stopped and no fluid is being pumped into the 35 system, the balls 36 will be disposed at the inner portion of the groove 37 and lie adjacent the axis of rotation of the disc 30. In this position, the balls do not engage the disc 31, and the disc 31 will be in its lowermost position by virtue of 40 the action of gravity and the high pressure of the pumped fluid thereon. Since the valve pin 46 is at this time out of engagement with the seat in the bushing 45, communication will be established from the inlet connection through passageway 43, the chamber 42, the passageway 44 and thence to the outlet connection 17, whereby the pumping elements are by-passed and any 45 pressure which may be in the outlet connection due to previously running the pump, will be 50 equalized with the inlet pressure. This will enable the pump to be started under little or no load.

When the pump is started, the disc 30 will be 55 rotated and the ball retainer disc 34 will also rotate and revolve the balls around the stem 32. As the pump continues to come up to speed, a speed will be reached wherein the balls 36 will move outwardly under the influence of centrifugal force and will be slightly raised due to the inclined surface or bottom of the circumferentially extending groove, whereby the balls will be brought into engagement with the confronting face of disc 31, to raise the disc and bring the valve pin 46 against its seat. Seating of the valve pin will intercept communication through the chamber 42 between the passageways 43 and 44, whereupon the pumping element will not be by-passed and fluid will be pumped directly into the system.

From the foregoing, it will be apparent that the herein described invention describes novel means for seating of the rotative cylinders of the pump, and also provides a novel centrifugal device which automatically operates to control 75

the by-passing of the pump parts between the inlet and outlet connections of the pump, whereby when the pump is stopped, the outlet pressure is equalized with the inlet pressure so that the 5 pump may be started under little or no load condition.

I am aware that many changes may be made and numerous details of construction may be varied through a wide range without departing 10 from the principles of this invention and I, therefore, do not purpose limiting the patent granted hereon otherwise than necessitated by the scope and spirit of the appended claims.

I claim as my invention:

15 1. In a fluid pumping unit having a housing enclosing pumping elements, and inlet and outlet connections for fluid to be pumped; a rotatably mounted member projecting to the exterior of the housing, said member being rotatable in accordance with the pump speed, a cap disposed 20 over the projecting end of said member and cooperating with the housing to define a chamber, a passageway from said outlet terminating centrally of the top of the cap and defining a valve 25 seat, a valve element associated with said seat, another passageway connecting said chamber

and the inlet, and centrifugally operated means responsive to the movement of said member for actuating the valve element to control the flow of fluid through the passageways and chamber, said passageways and chamber cooperating to 5 form a by-pass between the pump inlet and outlet connections.

2. A fluid pumping unit comprising an elongated housing, pumping means in said housing including a rotatable member, inlet and outlet connections for said means, a cap removably and abuttingly secured to one end of the housing and cooperating therewith to form a chamber, passageways in the housing wall and cap wall connecting the inlet and outlet connections with 10 said chamber to form a by-pass therethrough, a passageway in the cap wall being in end to end registration with a passageway in the housing wall, the other end of the cap passageway terminating in the cap wall to define a valve seat, 15 and a centrifugally operated valve mechanism in said chamber connected for actuation from said rotatable member and cooperable with said seat for controlling the flow of fluid in said by-pass. 20 25

CHARLES L. RAYFIELD.
